UNITED STATES PATENT OFFICE.

**NORMAN LIPSKY, OF NEW YORK, N. Y., ASSIGNOR TO SUN RISE LAMP MFG. CO., INC.,
A CORPORATION OF NEW YORK.**

DESIGN FOR FRAME FOR LAMP SHADES, LANTERNS, OR SIMILAR ARTICLES.

Application filed May 16, 1924. Serial No. 9,626. Term of patent 3½ years.

To all whom it may concern:

Be it known that I, NORMAN LIPSKY, a citizen of the United States, and a resident of the city, county, and State of New York, have invented a new, original, and ornamental Design for Frame for Lamp Shades, Lanterns, or Similar Articles, of which the following is a specification, reference being had to the accompanying drawing, forming a part hereof.

The drawing shows an elevational view of the frame for lamp-shades, lanterns, or similar articles.

I claim:

The ornamental design for frame for lamp-shades, lanterns, or similar articles substantially as shown.

NORMAN LIPSKY.
